UNITED STATES PATENT OFFICE.

SAMUEL B. WILLIAMS, OF NEW YORK, N. Y., ASSIGNOR TO WESTERN ELECTRIC COMPANY, OF NEW YORK, N. Y., A CORPORATION OF ILLINOIS.

TELEPHONE-EXCHANGE SYSTEM AND APPARATUS.

1,097,204.

Specification of Letters Patent.

Patented May 19, 1914.

Application filed December 20, 1909. Serial No. 533,986.

To all whom it may concern:

Be it known that I, SAMUEL B. WILLIAMS, citizen of the United States, residing at New York, in the county of New York and 5 State of New York, have invented a certain new and useful Improvement in Telephone-Exchange System and Apparatus, of which the following is in full, clear, concise, and exact description.

10 This invention relates to telephone exchange systems, and particularly to telephone exchange systems which employ automatic ringing for signaling purposes and which are equipped with trunk lines leading 15 to private branch exchanges, chief operators' desks and like positions.

As applied to ordinary subscribers' lines automatic or keyless ringing has proven eminently satisfactory, but when employed in 20 signaling between offices connected by trunk lines, for instance between a central office and a private branch exchange, or between one operator's position and another's, such as between an answering operator and a chief 25 operator's desk, the method of applying automatic ringing has been found to possess an inherent defect which manifests itself in the form of an objectionable click in the ear of the answering operator upon the depression of the listening key in response to 30 a call, since she thereby brings her telephone directly into a circuit upon which ringing current is being impressed, which ringing current is thereupon cut off, but not before it 35 has given her the disagreeable click referred to, due to the action of the central office mechanism in transferring the trunk leads from the source of ringing current to the 40 source of battery current upon the depression of the listening key. This objection is not met with in signaling an ordinary subscriber for the reason that the mechanism at the central office operates and disconnects ringing current from the line and substitutes 45 talking current therefor in the interval between the time he removes his receiver from its hook and the time he places it to his ear. It is very desirable that this objectionable 50 feature be eliminated.

55 The present invention has that purpose as its object, and consists in providing a circuit arrangement whereby upon the depression of the listening key by the answering operator in response to a call, a relay is included in the circuit and is adapted upon its

energization to cause the disconnection of the ringing current from the line, and the actuation of means to thereafter include the operator's telephone set in circuit, thus providing for the inclusion of the telephone set 60 in circuit after the ringing current has been disconnected.

More specifically the invention consists in providing a relay adapted to be included in the ringing circuit upon the depression of 65 the listening key and in its actuation to provide an increase in the strength of the ringing current to operate a marginal relay at the calling board to shift the leads from a source of ringing current to a source of direct current, the consequent flow of direct current causing the actuation of a direct current relay at the called position to include an operator's telephone in circuit. 70

The apparatus at the central office for signaling the wanted private branch exchange or other operator may comprise the usual apparatus employed in automatic ringing and for the purpose of this invention it will be sufficient to say that it consists of a source 75 of alternating current and a source of direct current so connected with the lead to the ringing circuit that the insertion of the plug will bring about the actuation of means adapted to impress current from the alternating source upon the line for a certain interval, say two seconds, when it is succeeded by a silent period of say three seconds, 80 during which time the lead to the ringing circuit is connected to the battery source and direct current is caused to pass out over the line in substitution of the alternating current. Should the listening key be depressed during a silent period, the means which 85 controls the application of ringing current is rendered active to bring about the disconnection of both of said sources of current and incidentally to cause the leads to the trunk to be connected to a source of battery current from the cord circuit, which holds 90 up the relay which connects the operator's telephone set in circuit. 95

I have illustrated my invention as embodied in a telephone exchange equipped with a keyless automatic ringing cord circuit, but I do not wish to be understood as limiting myself to the precise form shown, since any system wherein an intermediate device arranged to be operated by the ringing current to disconnect the same from the 100 105 110

line and thereafter cause the inclusion of a telephone in circuit would be within the scope of this invention.

The invention will be more readily understood by reference to the accompanying drawing, which is a diagram illustrating the invention as embodied in a telephone exchange system and wherein is shown the keyless automatic ringing cord circuit terminating in a plug which is adapted for connection with the jack of a trunk leading to a desk operator's position.

The same letters of reference designate the same parts wherever they are shown.

15 The switchboard A is the calling board and the operator thereat for convenience will be designated the A operator. The switchboard B is the answering board and the operator thereat will be called the 20 answering operator. Each trunk may terminate at the B or answering board in a signal actuating device as shown, which in the present instance is a ring-down relay 26, and may also have connection with a 25 plug for answering the call. For clearness of illustration, however, the plug is omitted, as is also the plug which may be connected to the conductors 4, 4^a, where they are broken off, to extend the call to a subscriber's line terminating at the answering board. The dotted line indicates the division of the circuit between the exchanges, that to the left of the line being located at the switchboard A and that to the right being located 35 at the answering board, the trunk line being indicated by the numerals 4, 4^a. A listening key is also provided individual to each trunk and is adapted upon its depression to close a circuit for a magnet common 40 to all the trunks which upon its energization disconnects the ringing current from the line and thereafter brings about the actuation of a relay adapted to include an operator's telephone set in circuit.

45 Referring to the drawings the three limbs 1, 2, 3 of the cord circuit at the A board terminate in a plug adapted for insertion into the jack of the trunk line 4, 4^a which leads to the answering board B. This plug 50 when inserted into the jack is arranged to close a circuit from a battery 6 to the grounded sleeve of the jack and cause the illumination of the supervisory lamp 7. A relay 8 in the path of the battery current 55 to the trunk line controls the illumination of this signal, being adapted upon its actuation, which occurs when the desk operator has answered the call, to close a shunt circuit comprising the resistance 18 and the 60 conductor 9 about said lamp and thereby darken the same, and afterward when the connection is taken down by the answering operator to again become inert and allow its armature to fall back, thereby removing the 65 shunt and again causing its illumination.

The relay 5 is provided with an armature 10 which is adapted to be drawn up to close its contact upon the energization of said relay, the said armature being grounded. From the grounded armature 10 a conductor 70 11 extends and branches at 12 into multiple paths 13, 14 and unites again at 15, whence it continues by conductor 16 to a relay 17, conductors 16, 48, resistance 18 to a battery 19. A relay 20 as included in the branch 75 circuit 13, the said relay being normally short-circuited by conductor 14, armature 24^a, its back contact, conductor 21, its own armature, to point 15, where it unites with conductor 16. The relay 17, however, is 80 adapted to respond to the current flowing in this circuit, and upon its energization to attract its armatures 24, 25.

From the source of ringing current 22 a conductor 23 leads to the front contact of an 85 armature 24 of relay 17, and when said armature is attracted, to the ring of the plug, adapted to register with the ring of the jack, and thence by way of conductor 4, through bridge 28 including a ring-down 90 relay 26 and condenser 42, and back to ground by way of conductor 4^a, the tip of the jack, the tip of the plug, conductor 1, armature 25 and its front contact to the grounded conductor 27. The ring-down relay 26 is responsive to alternating current in 95 this circuit and is bridged across conductors 4, 4^a through a condenser 42. A relay 38 is included in the ringing circuit just traced, but is marginal in operation and will not 100 respond to the ringing current applied to the line by the apparatus 22. This relay is, however, adapted promptly to respond upon its inclusion in a direct current circuit.

At the answering board the usual listening key 29 is provided individually to each trunk, a contact of the said key normally completing a circuit with conductor 30 leading to the armature of the ring-down relay 26 which is adapted when attracted to close 105 a holding circuit including a battery 49, for the illumination of lamp 32 in a circuit from battery 43 to ground at 44 to indicate to the operator that conversation is desired, the depression of said key by the operator in responding opening said circuit at contact of conductor 30 and extinguishing said signal. The listening key is connected with conductors 33, 33^a and upon its depression is adapted 110 to extend the circuit of line conductors 4, 4^a to conductors 33, 33^a. A bridge 45 of conductors 33, 33^a is rendered non-conductive to battery current and is also rendered of relatively high impedance to the high 115 frequency talking current by reason of the inclusion therein of a condenser 35 of suitable capacity for such purpose, and a relay 34 of high resistance. The relay 34 controls at its armature a path of low resistance 120 in multiple with bridge 45, including a low 125 130

non-inductive resistance 35^a, the said path being closed upon the energization of said relay which occurs upon the depression of the listening key 29 in answer to a call. 6 Bridged across conductors 33, 33^a in series with the resistance 35^a and a retardation coil 41 is a relay 36 adapted to respond to direct current only, and to include an operator's telephone set 37 in circuit with conductors 33, 33^a. This relay will not respond to the alternating current adapted to operate relay 34 because of the inclusion of the impedance coil 41 in its circuit, and in addition the relay may be made sluggish in 15 its action so as not to respond to short impulses. The purpose of the resistance 35^a is to prevent an excess of current through the winding of relay 36 should the operator depress the listening key during a silent interval when direct current from the battery 22 is being impressed upon the line. Upon the response of the called operator by the depression of listening key 29, the relay 34 instantly closes at its armature contact the 20 low resistance path including the non-inductive resistance 35^a and permits of an adequate increase in the flow of current in the circuit for the operation of relay 38 in the circuit of the A board. The condenser 50 bars the passage of direct current to the operator's telephone set 37. The relay 38 controls at its armature contact a short circuit of relay 20 and upon its excitation is adapted to attract its armature and open the short 25 circuit, about said relay, thereby causing its energization, which relay thereupon operates and at its front contact closes a short circuit of relay 17, causing the deenergization of said relay, and the armatures thereof fall back and transfer the connections of the 30 trunk to the source of battery current 40. This battery may be bridged across the cord circuit conductors 45, 46 through the usual repeating coil 47 and may be of say 24 volts. 35 The operation of the system of this invention is as follows: Assuming the A operator has selected the jack connected with a desired trunk, she inserts the plug therein. A circuit is now completed for the illumination 40 of the lamp 7, and may be traced from battery 6 by way of conductor 3, the sleeve strand of the plug which registers with the sleeve of the jack, to ground through a resistance, causing the illumination 45 of the signal 7, and the energization of relay 5. Its armature is thereupon attracted and closes a circuit from the grounded armature 10, conductors 11, 14, armature 24^a of relay 38, conductor 21, armature of 50 relay 20, conductor 16, relay 17, conductors 16 and 48, to battery 19. The relay 20 being thus short-circuited cannot operate. The relay 17, however, is now energized and draws up its armatures 24, 25 completing a 55 circuit for applying ringing current to the trunk line which may be traced as follows: from the grounded generator 22, conductor 23, relay 38, conductor 23, front contact of armature 24, conductor 2, ring of the plug, ring of the jack, conductor 4, and through 60 the bridge 28 including condenser 42 and relay 26 back to ground by way of conductor 4^a, tip of the jack, tip of the plug, conductor 1, armature 25, conductor 27 to ground. The relay 38 is included in the circuit just traced, but since it is marginal in operation, as before stated, it is not energized by this flow of current, but the ring-down relay 26 is energized and attracts its armature, thus closing a holding circuit for 65 said relay from battery 49 to ground at 44, which maintains a closed path for the illumination of the lamp 32 from a battery 43 to ground at 44 to notify the operator of the call, to which she will respond by depressing her listening key. A multiple path is thus provided for the ringing current through the contacts of the listening key 29, conductor 33, through the bridge 45, including condenser 35 and relay 34, and 70 back over the other side of the line by way of conductor 33^a, contact of key 29, to conductor 4^a and ground at 27 over the path previously traced. The relay 34 is now operated and closes at its front contact the 75 low resistance path including resistance 35^a, which allows of an adequate increase in the current flow for the energization of the marginal relay 38 at the A board, which thereupon attracts its armature 24^a and breaks 80 the short circuit of relay 20, which is then energized and attracts its armature, thus breaking connection with its back contact and making connection with its front contact which places a short circuit about magnet 17, and locks itself up in a circuit which may be traced from the grounded armature 10, conductors 11, 13, the relay itself, its armature and front contact, conductor 48 to the grounded battery 19. The relay 17 being now deenergized, allows its armatures 85 24, 25 to make connection with their back contacts which lead to the terminals of a battery 40 bridged across conductors 45, 46 through the usual repeating coil 47. Current from said battery now flows out over the trunk line and may be traced from the free pole of said battery, repeating coil 47, conductor 46, including relay 8, back contact of armature 24, conductor 2, ring of the 90 plug, ring of the jack, conductor 4, contact of key 29, conductor 33, resistance 35^a, retardation coil 41, relay 36, conductor 33^a, contact of key 29, conductor 4^a, tip of the jack, tip of the plug, conductor 1, armature 25 and its back contact, conductor 45, repeating coil 47 to the opposite pole of battery 40. The relay 36 is now operated and attracts its armatures thus bringing the operator's telephone set into the circuit just 95 100 105 110 115 120 125 130

traced. The relay 8 is in the circuit just traced and is adapted to be energized to attract its armature, thus shunting out the lamp 7, which will indicate to the calling operator that the call has been answered.

The sequence of operations just traced occurs should the operator at the desk position depress her listening key during a ringing interval. The operation of the circuit, should the operator depress her listening key during a silent interval, will now be explained. As before stated, during the silent interval direct current from the source of current 22 is being impressed upon the line. This source of current may in practice be approximately 110 volts. The relay 38 is wound to respond to current from said source. It will be readily apparent therefore that should the answering operator depress her listening key during a silent interval, the relay 36 will immediately be energized and attract its armatures, thus bringing the operator's telephone into circuit, current from the same source, however, having already energized relay 38 which attracts its armature 24^a causing the energization of relay 20, which attracts its armature and short circuits relay 17, the latter's armature 24 thereupon disconnecting itself from the lead to the source of ringing current and completing, with armature 25, a circuit to the answering board including the source of current 40 to hold up relay 36. Upon the taking down of the connection at the desk operator's position, the circuit of relay 8 will again be broken and its armature will fall back removing the shunt 9 about lamp 7 and thereby causing its illumination to notify the A operator of the termination of the call, when she will withdraw the plug from the trunk jack, whereupon the apparatus will be restored to normal.

While for convenience of illustration, several batteries are shown it will of course be understood that these sources of current, where they are of the same polarity and located in the same exchange, may be, and in practice are one and the same battery.

Having thus described my invention, I claim:

1. The combination with an electric circuit and means for supplying ringing current at one point in said circuit, of an electro-responsive device included in said circuit at another point, automatic means actuated upon the response of said device to said ringing current to disconnect said ringing current from said circuit, a source of direct current, telephone apparatus normally disconnected from said circuit, and means responsive to said direct current after cessation of said ringing current flow in said circuit to connect said telephone apparatus thereto.

2. The combination with an electric cir-

cuit, of a source of current, means for applying said current to said circuit, a relay, a switch adapted to include said relay in said circuit, a second relay actuated in the response of said first mentioned relay for disconnecting said source of current from said circuit, telephonic apparatus, and a switch actuated in the response of said first mentioned relay adapted to connect said telephonic apparatus in circuit, whereby the telephonic apparatus is not connected in circuit until said source of current has been disconnected.

3. The combination with a telephone switch-board, of an electric circuit associated therewith, a source of ringing current, means for applying said current to said circuit, an electro-responsive device included in said circuit, means actuated upon the response of said device to said ringing current to disconnect said ringing current from said circuit, a source of direct current, telephone apparatus normally disconnected from said circuit, and means responsive to said direct current after cessation of said ringing current flow in said circuit to connect said telephone apparatus thereto.

4. The combination with two telephone switchboards, of a circuit connecting said switchboards, a source of ringing current, means at one of said switchboards for applying said ringing current to said circuit, an electro-responsive device included in said circuit at the other of said switchboards, means actuated by said ringing current in said circuit upon the response of said device thereto to disconnect said ringing current from said circuit, a source of direct current, telephone apparatus normally disconnected from said circuit, and means responsive to said direct current after cessation of said ringing current flow in said circuit to connect said telephone apparatus thereto.

5. The combination with two telephone switchboards, connected together by a pair of conductors, means at one of said boards adapted to complete a circuit for said conductors and to apply ringing current over said conductors to said other board, a signal operated thereby, a listening key adapted to be depressed in response to said signal, and to include a relay in said circuit, the response of said relay causing the disconnection of the ringing current from the circuit and the inclusion of an operator's telephone set therein.

6. The combination with an electric circuit, of a source of ringing current, means for applying said ringing current to said circuit, a switch, a relay responsive to the closure of said switch, means actuated upon the response of said relay for disconnecting said ringing current from said circuit and substituting a source of direct current therefor, telephonic apparatus, and means actu-

ated by said direct current for including said telephonic apparatus in said circuit.

7. The combination with an electric circuit, a source of ringing current, means for applying said ringing current to said circuit, a switch, a relay responsive to the closure of said switch, said relay in its response causing the disconnection of said ringing current from said circuit and the substitution of direct current therefor, telephonic apparatus, and a relay actuated by said direct current for including said telephonic apparatus in said circuit.

8. The combination with a calling switchboard A, an answering switchboard B, and a telephone trunk line uniting said switchboards, a source of ringing current at said A board, means for applying said current over said trunk to the B board, a switch at said B board, means at the A board operative upon the actuation of said switch for disconnecting said ringing current from the trunk line and substituting direct current therefor, a normally open circuit at the B board including an operator's telephone set, and means actuated by said direct current for closing said circuit through said trunk line.

9. The combination with two telephone switchboards at each of which telephone lines are centered, of a trunk line uniting said switchboards, a source of ringing current at one of said boards a signal at the other board, means for applying said current to said signal, a switch adapted to be actuated in response to said signal, a relay at said last mentioned board adapted to be energized by said ringing current upon the actuation of said switch and adapted to close a low resistance path for said current, an electrically controlled switch at the first mentioned board, the resultant increase in current causing said electrically controlled switch to disconnect said ringing current from the line and substitute therefor direct current, an operator's telephone set in a nor-

mally open circuit at said last mentioned board, and a relay thereat adapted to be energized by said direct current to close said circuit through said trunk line.

50

10. The combination with two telephone switchboards at each of which telephone lines are centered, a telephone trunk line uniting said boards, a ringing generator at one of said boards, a signal at the other board, means for applying current from said generator to said trunk line to operate said signal, a listening key, a relay at said last-mentioned board energized upon the depression of said listening key, and arranged to close a low resistance path for said current, the resultant increase in current serving to operate means at said first-mentioned board for disconnecting the said generator from the line and substituting a source of direct current therefor, an operator's telephone set in a normally open circuit at said other board the leads to said circuit being arranged to be connected in the circuit of the trunk line by an electromagnetic switch actuated by said direct current.

55

11. The combination with two telephone switchboards at each of which telephone lines are centered, of a trunk line uniting said boards, means at one of said boards for applying ringing current over said trunk line to the other board, and a switch actuated by the operator at that board for disconnecting said ringing current from the line and substituting direct current therefor, and an electrically operated switch at said last named board, responsive to said flow of direct current, for uniting to said trunk line a circuit including an operator's telephone set.

70

In witness whereof, I hereunto subscribe my name this eighteenth day of December A. D. 1909.

SAMUEL B. WILLIAMS.
